UNITED STATES PATENT OFFICE

ORVILLE T. SMITH, OF BROOKLYN, NEW YORK.

COLLAR OR SLEEVE BUTTON.

SPECIFICATION forming part of Letters Patent No. 316,194, dated April 21, 1885.

Application filed January 12, 1885. (No model.)

To all whom it may concern:

Be it known that I, ORVILLE T. SMITH, of Brooklyn, in the county of Kings and State of New York, have invented a new and useful 5 Improvement in Collar and Sleeve Buttons, of which the following is a specification.

My invention relates to those collar and sleeve buttons in which the post is hollow or tubular and made from a continuous piece of 10 metal, without seam or joint, and more particularly to those buttons in which the post has the back plate or shoe formed integral with it.

The object of my invention is to enable the 15 heads of buttons of this class to be made of a fine grade of gold, and the post and back plate, which constitute the principal part by weight, to be made of a less fine grade of gold, whereby I produce a button which is equal in appearance to, and much less expensive than, a button having the head and post integral from one continuous piece of metal.

The invention consists in novel combinations of parts, hereinafter described, whereby 20 the desired result is attained.

In the accompanying drawings, Figure 1 is a 25 sectional view, on an enlarged scale, of a button embodying my invention. Fig. 2 represents that part which is to form the head, and Fig. 3 is a sectional view of the post and back plate ready to receive the head.

Similar letters of reference designate corresponding parts in all the figures.

A designates the hollow post, and B the 30 back-plate, of the button. The post A is made of one piece of metal without seam or joint, and, as here represented, the post and the back-plate B are formed integral from a single piece of sheet metal, and compose the principal part, by weight, of the button. The back-plate B has its outer edge rolled or turned inward, as shown at b, to give it a neat finish and thick edge, and there is formed at the upper or outer end of the post A an outwardly-extending flange, a, at the margin or border of which is an upturned rim, a*.

The head C consists of a cap of inverted cup

shape, which is made slightly larger in diameter than the rim a*, and is slipped over the same, as shown in Fig. 1. The edge of the 50 head or cap is turned inward, as shown at *, so as to slightly underlie the rounded corner at the junction of the flange a and rim a*, and thereby secure the head to the post A. The head C rests upon and is supported by the rim 55 a*, and the latter therefore serves to keep the head sufficiently apart from the flange a to make a head of the desired thickness.

The button constructed as above described may be made by means of suitable tools and 60 by the cheap and simple processes which are well understood by workers in sheet metal and jewelers.

The head of the button is alone visible when worn, and hence this is the part which it is most desirable should be highly finished. The post and back-plate make up almost the whole weight of the button, and a high finish thereof is not so necessary. A fine or high grade of 70 gold is susceptible of a fine finish, and by making the button as described I may employ a fine grade of gold for the head or smaller part, without the necessity of making the whole button of a fine grade of gold.

I am aware that it is not new to make a button with its head-post and back-plate all integral with each other from one continuous piece of metal without seam or joint; and I am also aware that it is not new to make a button with a flanged hollow post formed of a piece of sheet 80 metal bent into shape and having a seam lengthwise of the post, which seam must be soldered, and having a head made of a separate piece and secured to the flanged end of the post.

I make no claim to a button of either of the constructions above referred to, but desire to limit my invention to a button having a tubular post made in one piece without seam or joint, and provided at the outer end with 90 an integral flange, a, and upturned rim a*, and a cup-shaped head, C, made separate from and secured to the flanged end of the post in the manner herein described. It is very 85

desirable that the button shall be made without any soldering, as such operation weakens the metal by annealing it.

What I claim as my invention, and desire 5 to secure by Letters Patent, is—

The collar or sleeve button herein described, consisting of the tubular shank or post A, made in one piece without seam or joint, and having at the outer end a flange, a, and an upturned

rim, a*, both formed integral with the shank 10 or post, and a cup-shaped head, C, fitting outside the flange and rim a a*, and having its edge turned inward under the flange a, substantially as and for the purpose herein described.

ORVILLE T. SMITH.
